UNITED STATES PATENT OFFICE.

HARVEY FLETCHER, OF NEW YORK, N. Y., ASSIGNOR TO WESTERN ELECTRIC COMPANY, INCORPORATED, OF NEW YORK, N. Y., A CORPORATION OF NEW YORK.

TESTING SYSTEM.

Application filed November 20, 1922. Serial No. 601,958.

To all whom it may concern:

Be it known that I, HARVEY FLETCHER, a citizen of the United States, residing at New York, in the county of New York, State 5 of New York, have invented certain new and useful Improvements in Testing Systems, of which the following is a full, clear, concise, and exact description.

This invention relates to testing systems, 10 and particularly to a system for determining the efficiency of a telephone transmission line.

The object of the invention is, in general, 15 to provide a convenient and efficient system for readily determining the efficiency of a transmission line such as a subscriber's loop although in its broader aspects the invention is not limited to this use.

In accordance with the general features 20 of the invention, a subscriber's loop is tested by supplying a definite amount of alternating current energy over the loop to an impedance which has a value that is very large in comparison to the impedance of the loop, 25 and then supplying the same amount of energy over the loop to an impedance which is commensurate with the impedance of the loop. By making the proper comparison between the two voltages, which cause the 30 energy to be supplied in the two cases, a measure of the efficiency of the loop is obtained.

In the form of the invention illustrated, 35 the impedance to which the energy is supplied, takes the form of a transformer in which the primary winding is arranged to have an alternative number of active turns, and the secondary winding is connected to a telephone receiver. The constants of the 40 transformer are such that with the receiver connected to the secondary winding, the impedance looking into the smaller number of primary turns is equal to the impedance of a standard subscriber's set. The impedance looking into the entire primary winding is 45 very high in comparison to the impedance of the loop and hence when energy is supplied to the receiver with the transformer connected so that the entire primary winding is active, the impedance of subscriber's loops met in practice has a negligible effect 50 and hence can be assumed to be zero, which

is the same as the impedance of a zero loop.

Referring to the drawings:

Fig. 1 shows schematically a subscriber's 55 loop with the connected apparatus used in making a test.

Fig. 2 shows an alternative arrangement 60 of the central office apparatus shown in Fig. 1.

Fig. 3 shows characteristic curves giving 65 the relation between the direct current resistance of a certain type of carbon transmitter, and the alternating voltage generated by the transmitter when it is subjected to various degrees of agitation.

In order to make a test two men are required, one to make the circuit change and adjustment at the central office, and the other to make them at the subscriber's station. Resistance 1, which has a value equal 70 to the resistance of a subscriber's transmitter when subjected to standard agitation, is substituted for the subscriber's transmitter. Resistance 2 is then adjusted until meter A₁ 75 shows that a direct current of the desired value, e. g., 90 milliamperes, is flowing from battery 3 through winding 4, line conductor 5, resistance 1, choke coil 12, line conductor 6, and winding 7. Condensers 50, 51, 80 52 and 53 are provided to exclude the direct current from undesired portions of the circuit and hence it is confined to the path just traced. Resistance 1 is then replaced by transmitter T.

If desired, the substitution 85 of resistance 1 for the transmitter T and vice versa, may be accomplished by means of a switch 8. With switch 20 connected to terminal 21, a resistance 9 is adjusted until the alternating current voltmeter V₁ shows 90 that voltage of a desired standard value, e. g., 10 volts, is being supplied to the line by generator 10, which preferably is a band frequency generator that delivers current having an energy-frequency spectrum similar 95 to voice current. The alternating current is transmitted over the subscriber's loop and energizes receiver R, which is placed in bridge of the line by means of the transformer which comprises primary winding 13 and secondary winding 14. With switch 20 connected to terminal 21 the impedance 100 of the transformer looking into winding 13 is very high compared to the

2 impedance of the loop and hence a definite voltage, as indicated by voltmeter V_1 , will cause receiver R to give, for practical purposes, the same sound output regardless of 5 the length of the subscriber's loops which are met in practice. In other words, the condition is such that the amount of current being supplied over the loop is so small that the voltage drop between the central 10 office and the subscriber's station is negligible and hence the effect is the same as if the loop had zero impedance. Choke coil 12 keeps the above mentioned alternating current from flowing through transmitter T 15 and condenser 18. The receiver which is now giving a definite sound output is acoustically coupled to the transmitter thus subjecting the transmitter to an amount of agitation which is a function of the energy 20 which is being supplied over the loop to the receiver. If desired, a tube 15 may be used to inclose an air column between the transmitter and the receiver.

The agitation of the transmitter causes 25 an increase in its resistance and hence a corresponding decrease in the deflection of meter A_1 which measures the direct current supplied to the transmitter by battery 3. The change in the deflection of meter A_1 is 30 a function of the increase in the resistance of transmitter T , which, in turn, is a function of the alternating voltage generated by the transmitter, as is shown by the curves in Fig. 3. For the example chosen, curve 35 b is the one of interest, as it shows the relation between the alternating voltage generated by the transmitter and the effective direct current resistance of the transmitter for the case where the steady state current 40 through the transmitter is 90 milliamperes. The alternating voltage generated by the transmitter is a function of the output of receiver R and hence the change in deflection of meter A_1 is a measure of the output 45 of receiver R which, in turn, is a measure of the alternating current energy being supplied over the transmission line.

Switch 20 is now transferred from terminal 21 to terminal 22. If resistance 9 50 is adjusted until meter A_1 indicates the same change in deflection, upon agitation of the transmitter T by receiver R as it did for the case where switch 20 was connected to terminal 21, it is apparent that the output 55 of receiver R is the same as it was when switch 20 was connected to 21. It is apparent, therefore, that the same amount of alternating current energy was supplied over the line for the two positions of 60 switch 20.

Meter A_1 must have a relatively high range, which for the example chosen would mean a full scale deflection of at least 90 milliamperes. The decrease of the direct 65 current caused by the agitation of the trans-

mitter may be so small that it cannot be 70 sufficiently accurate on the meter of such high range. To obtain more accurate readings, a second meter A_2 of lower full scale deflection, e. g., 15 milliamperes, may be inserted in series with meter A_1 and a battery 75 16 in series with resistance 17, used to set meter A_2 back so that it will be operable to indicate changes in a current of the order of 90 milliamperes. The change in deflection of meter A_2 upon agitation of the transmitter may therefore be used as a measure 80 of the output of receiver R .

The reading of voltmeter V_1 is noted after the adjustments have been made with switch 20 connected to terminal 22 and by 85 making the proper comparison between this value of voltage and the value of voltage for the case where switch 20 was connected to terminal 21, a measure of the transmission 90 efficiency of the subscriber's loop can be obtained. This may be seen from the following mathematical calculation.

Let:

Z_1 be the impedance looking in the taps 21 and 23 of the transformer with the receiver 95 of impedance R connected to the secondary winding 14.

Z_2 be the corresponding impedance looking in the taps 22 and 23.

M_1 be the mutual impedance between entire winding 13 and the winding 14.

M_2 be the mutual impedance between the section 22-23 of winding 13, and winding 14.

P_1 be the self impedance of entire winding 13 with winding 14 open.

P_2 be the self impedance section 22-23 of winding 13 with winding 14 open.

S be the self impedance of the secondary winding 14 with primary winding open.

$$Z_1 = \frac{P_1(S+R) - M_1^2}{S+R} \quad (1)$$

$$Z_2 = \frac{P_2(S+R) - M_2^2}{S+R} \quad (2)$$

The current in the receiver for the two connections is given by

$$I_1 = \frac{M_1}{S+R} \cdot \frac{E_1}{Z \sinh XL + Z_1 \cosh XL} \quad (3)$$

and

$$I_2 = \frac{M_2}{S+R} \cdot \frac{E_2}{Z \sinh XL + Z_2 \cosh XL} \quad (4)$$

Where:

I_1 is the current through the receiver for the case where the entire primary winding is active.

I_2 is the current through the receiver for the case where only section 22-23 of the primary winding is active.

E_1 is the voltage indicated by voltmeter

V for the case where the entire primary winding is active.

E_2 is the voltage indicated by voltmeter V for the case where only section 22-23 is active.

Z is the surge impedance of the subscriber's loop.

X is the propagation constant of the subscriber's loop.

10 L is the length of the loop.

When a zero loop is used, $L=0$ and equations (3) and (4) become

$$I_{10} = \frac{M_1}{S+R} \cdot \frac{E_{10}}{Z_1} \quad (5)$$

15 and

$$I_{20} = \frac{M_2}{S+R} \cdot \frac{E_{20}}{Z_2} \quad (6)$$

20 Where the addition of the subscript 0 to a character indicates that the character represents the quantity for the case where a zero loop is used,

25 Since resistance R is respectively adjusted so that receiver R has the same output when switch 20 is connected to terminal 21, and to terminal 22, it is apparent that the current passing through the receiver is the same in the two cases, or in other words $I_1=I_2$ also

$$30 I_{10}=I_{20}.$$

By making the adjustment so that $E_1=E_{10}$ we have the condition that,

$$I_1=I_{10}=I_2=I_{20}$$

$$\text{Efficiency} = \log_e \left[\frac{E_1}{E_2} \cdot \frac{M_1 Z_2}{M_2 Z_1} \right] = \log_e \frac{E_1}{E_2} - \log_e C \quad (13)$$

It is seen that equation (13) gives the efficiency of the loop in terms of a constant C and E_1 and E_2 which are the two voltages measured on any given loop for the two positions of switch 20. If transformer 30 were ideal C would be the ratio of the number of primary turns for the two positions of switch 20. For the actual transformer it can be determined from a test on a zero loop for which

$$\log_e C = \log_e \frac{E_{10}}{E_{20}}$$

80 In the not unusual case where the surge impedance of the loop is equal to the impedance of a standard subset, i. e., $Z=Z_2$, equation (9) becomes

$$85 \frac{E_{20}}{E_2} = \frac{1}{\sinh XL + \cosh XL}$$

$$90 \frac{E_{20}}{E_2} = \frac{1}{\frac{\epsilon^{XL} - \epsilon^{-XL}}{2} + \frac{\epsilon^{XL} + \epsilon^{-XL}}{2}}$$

$$\frac{E_{20}}{E_2} = \epsilon^{-XL}$$

$$I_2 = \frac{M_2}{S+R} \cdot \frac{E_{20}}{Z_2} \quad (7) \quad (\text{from equation 6})$$

Dividing equation (4) by equation (7)

$$1 = \frac{E_2 Z_2}{E_{20} (Z \sinh XL + Z_2 \cosh XL)} \quad (8)$$

$$\therefore \frac{E_{20}}{E_2} = \frac{Z_2}{Z \sinh XL + \cosh XL} \quad (9)$$

This is the ratio of the voltage at the substation end of the line to the voltage at the central office end of the line when the definite amount of energy is being delivered to an impedance which is equal to the impedance of a standard subset, and hence is a measure of the efficiency of the loop. If desired the efficiency may be expressed as

$$\text{Efficiency} = \log_e \frac{E_{20}}{E_2} \quad (10)$$

Since $I_{10}=I_{20}$ we can equate the right-hand members of equations (5) and (6) and solve for E_{20} whence

$$E_{20} = \frac{M_1 Z_2}{Z_1 M_2} E_{10} \quad (11)$$

$$E_{20} = \frac{M_1 Z_2}{Z_1 M_2} E_1 \text{ since } E_{10} = E_1 \quad (12)$$

Placing the value of E_{20} in (10)

The expression for the efficiency,

$$\log_e \frac{E_{20}}{E_2}$$

is then equal to $-XL$ which gives the efficiency in napiers.

In cases where the length of loops being measured vary considerable it is sometimes desirable to use the alternative arrangement of central office apparatus as shown in Fig. 2. This arrangement is the same as shown in Fig. 1 except that there are inserted impedances 31 having values such that the impedance looking into the repeating coil from the loop side is equal to that obtained when an average telephone connection is made. The voltmeter for measuring voltage applied to the line is then placed as indicated at V_2 instead of as indicated at V_1 in Fig. 1. With this arrangement the measurements are made in exactly the same manner as previously described. In this case the equations which were obtained in deriving the efficiency of the loop contain a term for impedances 31, but the final expression for the loop efficiency is the same, viz,

$$\text{Efficiency} = \log_e \frac{E_1}{E_2} - \log_e C$$

In this case the constant C is equal to

$$\frac{M_2(Z_1 + A)}{M_1(Z_2 + A)}$$

5 instead of

$$\frac{M_2 Z_1}{M_1 Z_2}$$

where A is the combined value of the two 10 impedances 31. This constant may be obtained in the manner previously described by a test on a zero loop in which case

$$\log_e C = \log \frac{E_{10}}{E_{20}}$$

15 In the specification, mention has been made of values of current and voltage, but it is to be understood that these values are merely 20 illustrative, and that values of voltage, current, and impedance should be chosen which are the most suitable for the apparatus involved.

The invention claimed is:

1. In a system for measuring the efficiency 25 of a transmission line, a transmission line, a transmitter in bridge of said line, a receiver connected in bridge of said line by means of a transformer which has an alternate number of turns, means for sending direct 30 current over the line to said transmitter, means for sending alternating current over the line to energize said receiver, and means for measuring the voltage which causes said alternating current to flow.

35 2. In a system for measuring the efficiency of a transmission line, a transmission line, a transmitter and a receiver in bridge of said line, means for sending direct current over the line to said transmitter, means for sending alternating current over the line to 40 energize said receiver, means for varying the impedance which said receiver offers to said alternating current, and means for substantially excluding said alternating current from said transmitter.

45 3. In a system for measuring the efficiency of a transmission line, a transmission line, a transmitter and a receiver in bridge of said line, means for sending direct current over the line to said transmitter, means for sending alternating current over the line to energize said receiver, means for varying the impedance which said receiver offers to said alternating current, said alternating 50 current having energy frequency spectrum corresponding approximately to voice current, and means for measuring the voltage

which causes said alternating current to flow.

4. In a system for measuring the efficiency 60 of a transmission line, a transmission line, a transmitter and a receiver in bridge of said line, means for sending direct current over the line to said transmitter, means for sending alternating current over the line to energize said receiver, means for varying the impedance which said receiver offers to said alternating current, means for measuring the voltage which causes said alternating current to flow, and means responsive to 70 changes in the direct current through said transmitter.

5. In a system for measuring the efficiency 75 of a transmission line, a transmission line, a transmitter and a receiver in bridge of said transmission line, means for sending direct current over the line to said transmitter, means for sending alternating current over the line to energize said receiver, means for varying the impedance which said receiver offers to said alternating current, means for measuring the voltage which causes said alternating current to flow, means for substantially excluding said alternating current from said transmitter, and 80 means responsive to changes in the direct current through said transmitter.

85 6. A method of determining the efficiency of a telephone loop which comprises delivering a definite amount of energy over the 90 loop to an impedance which is large relative to the impedance of the loop, delivering a definite amount of energy over the loop to an impedance which is approximately equal 95 to the impedance of a telephone subset, and comparing the two voltages which cause said amounts of energy to be delivered.

100 7. A method of determining the efficiency of a transmission line which comprises delivering a definite amount of energy over said line to a telephone receiver which is connected in bridge of the line so as to offer an impedance which is large in comparison 105 to the impedance of the line, delivering a definite amount of energy over said line to said telephone receiver connected in bridge of the line so as to offer an impedance which is commensurate with the impedance of the line, and comparing the two voltages which cause said amounts of energy to be delivered. 110

In witness whereof, I hereunto subscribe my name this 17th day of November, A. D. 1922.

HARVEY FLETCHER.
